UNITED STATES PATENT OFFICE.

CHARLES A. PRATT, OF CHICAGO, ILLINOIS, ASSIGNOR TO GOODMAN MANUFACTURING COMPANY, OF CHICAGO, ILLINOIS, A CORPORATION OF ILLINOIS.

POWER-SHOVEL.

1,340,498.

Specification of Letters Patent. Patented May 18, 1920.

Application filed June 9, 1913, Serial No. 772,521. Renewed October 10, 1919. Serial No. 329,889.

To all whom it may concern:

Be it known that I, CHARLES A. PRATT, a citizen of the United States, residing at Chicago, in the county of Cook and State of

5 Illinois, have invented a certain new and useful Improvement in Power-Shovels, of which the following is a specification.

This invention relates to power driven shovels for handling bulk material such as 10 coal, broken stone and the like and has for its object to provide a device for depositing it into cars or other receivers.

The invention is illustrated in the accompanying drawings wherein—

15 Figure 1 is a plan view with parts broken away, illustrating one form of the power shovel as is used in a mine for shoveling loose coal into cars;

Fig. 2 is a side elevation in part section 20 showing one form of the device;

Fig. 3 is an enlarged plan view;

Fig. 4 is a side view of the shovel beam;

Fig. 5 is a plan view of the shovel beam;

25 Fig. 6 is a cross-sectional view through the shovel beam;

Fig. 7 is a sectional view taken on line 7—7 of Fig. 3.

Like parts are indicated by like letters throughout the several figures.

30 For the purpose of illustration I have shown the power shovel in use in a mine for the purpose of shoveling the coal into cars after it has been shot down, so that it can be hauled away.

35 As herein illustrated, the power shovel consists of three principal groups of parts, viz: a base A, a turntable B, and a shovel C. The base is held firmly in place by any suitable arrangement of jacks. In Fig. 1, 40 two sets of jacks are shown, each set consisting of two jacks in diagonally opposite corners. Jacks A¹ are used when loading car 1, and jacks A² are used when loading car 2. The base A carries a pivot A³ upon

45 which the turntable B is centered. It also carries a circular rack A⁴ with which pinions B¹ and B² mesh. These pinions are mounted on the turn table and are supplied with power, thus providing a means for revolving the turntable with reference to the base.

50 Base A also carries a circle of rollers for supporting the weight of the turntable, shovel and load. These rollers, A⁵, are suitably coned toward the center of the pivot A³. They revolve on studs A⁶ carried be-

tween an inner ring A⁷ and an outer ring A⁸. The circle of rollers travels in a race-way in the base, which keeps it concentric with the pivot.

Base A also carries rollers A⁹, which serve 60 to prevent the turntable from tipping when the loaded shovel is being raised.

The turntable B carries the power mechanism for revolving itself, and for actuating the shovel. The shovel, by this mechanism, 65 is given motion in a horizontal plane, outward from the center of the turntable or backward toward the center; it is also given motion in a vertical plane, revolving around the center of shaft B³. The turntable also 70 carries four guides B⁴ which serve to guide the shovel beam.

The power mechanism carried on the turntable, consists of a motor, air engine or other source of power, with speed reducing gearing necessary to drive shaft B⁵ at the proper speed.

75 B⁵ carries a pinion B⁶ which meshes with gear B⁷, which in turn meshes with gear B⁸. Gear B⁷ drives shaft B⁹ and gear B⁸ drives 80 shaft B¹⁰, and these shafts revolve in opposite directions. Gears B¹¹ and B¹² are mounted on sleeves on shafts B⁹ and B¹⁰, and are driven by these shafts through the friction clutches B¹³ and B¹⁴; the shifting mechanism B¹⁵ being so arranged that when B¹¹ is driven, B¹² revolves loosely on shaft B¹⁰, and vice versa, the shifting lever also having a central position in which neither B¹¹ or B¹² is driven. Gears B¹¹ and B¹² both mesh 85 with gear B¹⁶, which drives shaft B³. Shaft B³ drives gear B¹⁹, which meshes with the rack C⁴ on the shovel beam and drives the shovel. Since shifting mechanism B¹⁵ controls the direction in which shaft B³ revolves, 90 it also controls the motion, backward or forward of the shovel.

Keyed to shaft B⁹ is a sprocket wheel B¹⁷ which through a sprocket chain drives sprocket B¹⁸. Keyed to shaft B¹⁰ is a 100 sprocket wheel B¹⁹ which through a sprocket chain drives sprocket B²⁰. Sprocket wheels B¹⁸ and B²⁰ revolve in opposite directions and both are mounted on sleeves on shaft B²³ and this shaft may be driven by either 105 of these sprockets through friction clutches B²¹ or B²². The friction clutch shifting mechanism B²⁴, therefor, controls the direction in which shaft B²³ revolves, or B²⁴ may be set in a central position in which shaft 110

B²³ is undriven. Keyed to shaft B²³ is a friction brake pulley, B²⁵ and the band brake encircling this pulley is controlled by hand wheel B²⁶. Keyed to shaft B²³ is a wire 5 rope drum B²⁷. On this drum is wound a wire rope B²⁸, which is anchored at its center to the drum. One end is carried under sheave B²⁹, and attached to one end of the shovel cradle and the other end of B²⁸ is 10 carried under sheave B³⁰ and attached to the other end of the shovel cradle. By rotating shaft B²³ in one direction or the other, by means of the control given by shifting lever B²⁴, the wire rope is wound in one 15 direction or the other and thus the shovel is raised or lowered. By means of friction brake B²⁵, the shovel may be held at any elevation.

Mounted on the sleeve on shaft B⁹, is 20 bevel pinion B³¹ and this may be driven by shaft B⁹ through friction clutch B³³. Bevel pinion B³¹ drives gear B³⁵ which drives vertical shaft B³⁷ to the lower end of which is keyed pinion B¹, which meshes 25 with rack A⁴ and revolves the turntable. Mounted on a sleeve on shaft B¹⁰ is bevel pinion B³² and this may be driven by shaft B¹⁰ through friction clutch B³⁴.

Bevel pinion B³² drives bevel gear B³⁶ 30 which drives vertical shaft B³⁸ to the lower end of which is keyed pinion B², which meshes with rack A⁴ and revolves the turntable. Since shafts B⁹ and B¹⁰ revolve in opposite directions, the direction in which 35 the turntable is revolved is controlled by the friction clutches B³³ and B³⁴. The shifting mechanism for both of these clutches is controlled by one lever B³⁹, which in one position engages clutch B³³, in another position 40 engages B³⁴ and in a central position does not engage either.

Journalled on the shaft B³ is the shovel cradle. This consists of two similar and parallel arms B⁴⁰, one on either side of the 45 shovel beam. These two arms are joined together at one end by a cross piece B⁴¹, which passes below the shovel beam, and to which is attached one end of wire cable B²⁸, and they are joined together at the other 50 end by the cross piece B⁴² which passes below the shovel beam and to which is attached the other end of the cable B²⁸. The arms are also joined at this end by a cross piece B⁴³, which passes over the shovel beam 55 and provides a guide and clamp for the push rod C¹⁸. Each end of each of the arms B⁴⁰, carries a roller B⁴⁴ which run on the upper side of the lower flanges of the shovel beam, thus enabling the cradle to control 60 the vertical motion of the shovel.

The shovel consists of the scoop, the beam and the ejector. The beam as shown in Figs. 4, 5 and 6 is made of structural material and must be sufficiently strong to raise 65 the weight of material lifted by the scoop.

Fig. 6 shows a cross section of the beam which consists of two side members, C¹ joined together by a top member C² and an inner member C³. Attached to the lower side of C³ is the rack C⁴ by means of which gear 70 B⁴⁹ drives the shovel. At each side of the rack teeth is a bearing surface C⁵, which is at the level of the pitch line of the rack teeth and on which the weight of the shovel and the material is carried. Gear B⁴⁹ is provided with corresponding surfaces B⁵⁰ on its pitch circle. The cradle rollers B⁴⁴ run on the flanges C⁶. The shovel beam terminates in the casting C⁷ which carries the scoop on the trunnions C⁸. The brackets C⁹ provide 80 a support for the scoop latch C¹⁰ and may be of any desired dimensions. The scoop as shown is made of boiler plate or any other suitable material. It is strengthened and supported at the inner end by a member C¹¹ 85 which crosses the top of the scoop and extends down both sides to the trunnions C⁸. C¹¹ carries the catch C¹² with which the latch C¹⁰ engages. The latch C¹⁰ is opened by pulling the rope C¹³ which passes back 90 along the shovel beam and is attached to it at C¹⁴. There is attached to the outer end of the scoop, a shoe C¹⁵ which hangs on pivot C¹⁶, and forms a support for the end of the scoop, preventing it from digging 95 into the floor from which the material is being removed. The parts C¹⁷ may form one side of the scoop. It will be noted that the scoop has six sides and that two of its sides are open, viz: the forward side and 100 the top.

Fig. 1 shows the power shovel set and jacked in place suitably for loading into two cars. If the material is to be loaded into one car, the front jacks would have to 105 be set far enough back to permit the shovel beam to swing in both directions far enough to reach the material, and in one direction far enough to reach the car. The rear jacks also would have to be set far enough out and 110 back to give the necessary freedom of motion to the tail end of the shovel beam. This would result in greater width of base than would otherwise be necessary.

The shaft B⁵ carries a capstan B⁴⁷ on its 115 outer end. This, in conjunction with sheaves located as at B⁴⁸, and a rope anchored to a jack, is for use in moving the power shovel from place to place and in loading it on to its transporting truck. The 120 transporting truck may be similar to a mining machine truck and arranged for power drive from the shovel motor.

The use and operation of my invention are as follows:

When the device is used in a coal mine, for example, as shown in Fig. 1, and it is desired to load car 1, the shovel is brought into proximity to the coal to be handled and the jacks A¹ at opposite corners thereof are 130

placed in position, the bottoms of the jacks engaging the frame A and the tops of the jacks engaging the roof or some fixed part so as to hold the frame in position.

5 If it is desired to load car 2, the jacks A¹ are removed and the jacks A² placed in position so as to leave the shovel and beam free to move without striking the jacks

The scoop C is then moved down to the 10 floor and moved forward under the coal by revolving the shaft B³. After sufficient coal is on the scoop, the shaft B³ is stopped, the rotation of said shaft being controlled by the lever B¹⁵. The shaft B²³ is now rotated 15 so that the cable B²⁸ will be moved to pull down the rear end of the cradle and lift the scoop. When the scoop has been lifted, the rotation of the shaft is stopped, said rotation being controlled by the lever B²⁴. The 20 turntable B is then rotated by rotating the shaft B³⁷ or shaft B³⁸ depending upon which car is to be loaded. This rotation moves the scoop toward the car, as for example, car 1. When the scoop gets opposite the car or 25 above the car if the scoop is far enough forward, the rotation of the turntable is stopped. If the scoop is not far enough forward to be above the car, the shaft B³ is rotated so as to cause the gear B⁴⁹ to rotate 30 and since said sprocket is in engagement with the rack C⁴, the scoop will be moved forward. When in proper position above the car, the rotation of the shaft B³ is stopped. The rope or cable C¹⁸ is now pulled 35 so as to disengage the latch C¹⁰ from the member C¹². The weight of the coal now causes the scoop to drop, said scoop moving about the pivotal connection C⁸ so as to discharge the coal into the car. If for any reason 40 there is not room to permit the scoop to drop, the latch C¹⁰ is left in position and the bolt C²⁰ loosened so as to unclamp the rod C¹⁸. The bolt B⁴⁶ is tightened so as to clamp said rod to the cradle B⁴⁰. The shaft B³ is 45 now rotated in the opposite direction so as to move the scoop toward the shaft B³. The ejector C¹⁷ fastened to the rod C¹⁸ is now held against movement and the said ejector strikes the coal as the scoop is moved backward 50 and discharges it from the scoop.

It will be seen that by means of this device, material in bulk, such as coal, stone, sand or the like may be easily and quickly handled in large quantities, and may be 55 moved from one place to another and lowered into vehicles or handled for any other purpose desired.

I claim:

1. A power shovel comprising a base, a 60 turn-table mounted thereon, a shaft mounted on said turn-table, a rocking member mounted on said shaft, a supporting beam slidably connected with said rocking member, a scoop connected with said supporting beam, power

actuated means connected directly with said 65 rocking member at separated points on opposite sides of said shaft for moving said rocking member to move said supporting beam to lift the scoop, said shaft, rocking member and power-actuated means being located below the top of said supporting beam, a rack on said supporting beam, and a toothed wheel on said shaft engaging said rack, said rocking member and toothed wheel moving about the same axis. 75

2: A power shovel comprising a base, a turn-table mounted thereon, a shaft mounted on said turn-table, a rocking member mounted on said shaft, a supporting beam slidably connected with said rocking member, a scoop connected with said supporting beam, a flexible power-transmitting device connected directly with two parts of said rocking member on opposite sides of said shaft, direction-changing devices for said flexible 80 power-transmitting device located substantially in vertical alinement with the parts of said rocking member to which the said flexible power-transmitting device is connected, said shaft, rocking member, flexible power-transmitting device and direction-changing devices being located below the top of said 85 supporting beam, a rack on said supporting beam and a toothed wheel on said shaft engaging said rack, said rocking member and toothed wheel moving about the same axis. 90

3. A power shovel comprising a base, a turn-table mounted thereon, a shaft mounted on said turn-table, a rocking member mounted on said shaft, a supporting beam, a scoop carried by said supporting beam, said rocking member comprising two side pieces one on each side of the center line of said supporting beam, separated cross-pieces extending under said supporting beam and rigidly 100 connecting said side pieces and upon which said supporting beam rests and slides, power driven means for sliding said supporting beam along said cross-pieces, power-actuated means connected directly with said rocking member at separated points on opposite sides of said shaft for moving said rocking member to move said supporting beam to lift the scoop, said shaft, rocking member and power-actuated means being located below 105 the top of said supporting beam, and means for transmitting the weight of said supporting beam and scoop directly to said shaft so as to remove weight from said rocking member to facilitate the easy sliding of said supporting beam on said cross-pieces. 110

In testimony whereof, I affix my signature in the presence of two witnesses this 21st day of May 1913.

CHARLES A. PRATT.
